(57) **CLAIM**

The ornamental design for a folding container, as shown and described.

DESCRIPTION

FIG. 1 is a top perspective view of a folding container in a closed state in accordance with a first embodiment;
FIG. 2 is a top view thereof;
FIG. 3 is a right-side view thereof;
FIG. 4 is a left-side view thereof;
FIG. 5 is a bottom view thereof
FIG. 6 is a top perspective view of the folding container in an open state;
FIG. 7 is a top view thereof;
FIG. 8 is a front view of FIG. 7;
FIG. 9 is a side view of FIG. 7;
FIG. 10 is a bottom view thereof;
FIG. 11 is a top perspective view of a folding container in a closed state in accordance with a second embodiment;
FIG. 12 is a top view thereof;
FIG. 13 is a side view of FIG. 12;
FIG. 14 is a front view of FIG. 12;
FIG. 15 is a bottom view thereof;
FIG. 16 is a top perspective view of the folding container of the second embodiment in an open state;
FIG. 17 is a top view thereof;
FIG. 18 is a side view of FIG. 17;
FIG. 19 is a front view of FIG. 17; and,
FIG. 20 is a bottom view thereof.
The broken lines depict portions of the folding container that form no part of the claimed designs.

1 Claim, 4 Drawing Sheets
